PAVING BLOCK

Francis C. Sullivan, McKeesport, Pa.

Application November 14, 1939, Serial No. 304,356

4 Claims. (Cl. 94—12)

This invention relates to a paving block and particularly to a block adapted for the construction of railway crossings.

Various forms of railway crossings have been proposed heretofore but all of them with which I am familiar are characterized by serious defects. Timber floored crossings, for example, lack the desired durability, while other forms of construction which have longer life are undesirable for one reason or another. I have invented a novel form of paving block particularly suited for the construction of railroad crossings which entirely overcomes the objections to the crossing floors or paving which have been used heretofore.

In the preferred embodiment, the invention comprises a block having a tread portion of wear-resisting material such as cast iron and a body portion of non-metallic material such as concrete. The tread and body portions of the block are secured together by anchor members embedded therein. The blocks are of such dimensions that they may be easily laid side by side between the rails and on the outside of the latter to form a level pavement presenting a surface which is highly resistant to abrasion. Numerous other novel features and advantages of the invention will be pointed out during the course of the following detailed description which refers to the accompanying drawings illustrating the preferred embodiment.

In the drawings—

Fig. 1 is a view partly in plan and partly in section on a plane parallel to the tread surface;

Fig. 2 is a longitudinal section through a block, taken along the line II—II of Fig. 1 showing the block as installed at a crossing; line I—I of Fig. 2 illustrates the plane of the section shown in Fig. 1;

Fig. 3 is a transverse section through a railroad track having the blocks of my invention laid thereon to form a crossing;

Fig. 4 is a transverse section through a block taken along the line IV—IV of Fig. 2;

Fig. 5 is a similar section taken along the line V—V of Fig. 2;

Fig. 6 is a partial bottom plan view of the tread portion;

Fig. 7 is a partial section taken along the line VII—VII of Fig. 6;

Fig. 8 is a partial section through the tread portion before the formation of the body portion, showing an anchor member in an intermediate stage; and

Fig. 9 is a section showing a portion of Fig. 4 to enlarged scale.

Referring now in detail to the drawings, a paving block indicated generally at 10 comprises a tread portion 11 and a body portion 12. The tread portion is preferably of abrasion-resisting material such as cast iron and has its exposed surface roughened as by the formation of "diamonds" to provide good traction. The under-surface of the tread portion 11 is not flat but is grooved longitudinally and transversely as at 13 or otherwise shaped to provide preferred lines of fracture, for a purpose which will appear later. A peripheral skirt or apron 14 extends downwardly from the edge of the tread portion. This skirt or apron tapers inwardly toward the exposed surface of the tread portion. The tread has a longitudinal, depending rib 14a.

The tread portion 11 may conveniently be cast in a sand mold. Anchor members or struts 15 preferably in the form of double, twisted lengths of wire are embedded in the tread portion when the latter is cast. The grooves 13 provide a plurality of pyramidal projections 16 on the under-face of the tread portion and, as shown in Fig. 6, one of the members 15 is disposed centrally of each pyramidal projection. As shown in the drawings, the eyes at the doubled ends of the anchor members are embedded in the tread portion. The pattern for the tread portion may conveniently be slotted to receive the anchor members during the ramming of the mold. When the mold is completed and the pattern removed, the anchor members are supported with their eyes exposed in the mold cavity whereby they are embedded in the finished casting.

As shown in Figs. 8 and 9, the eyes in the anchor members 15 are large enough to permit the molten metal to flow therethrough, thereby forming a complete linkage which resists separation of the casting and the anchor member. Even in the absence of such complete linkage, however, the tapering outline of the eye resists such separation.

The wire from which the anchor members 15 are formed is of such size that there is practically no fusion, burning, nor crystallization thereof, by the heat of the molten iron during the casting of the tread portion. As a matter of fact, the anchor members have the effect of chilling the cast iron immediately adjacent thereto, thereby providing the latter with a close-grained surface and insuring a tight fit between the tread portion and the anchor members so that the latter are rigidly supported in

proper relation during subsequent manufacturing operations.

Elongated holes 17 are formed in the tread portion 11 near each end thereof adapted to receive suitable lifting tools. Necks 18 depending below the tread portion around the holes 17 have notches 19 formed therein at right angles to the longer dimension of the holes 17. The notches 19 are adapted to be engaged by the T-head of a lifting tool 20 when inserted through the holes 17 and turned 90°.

When the tread portion has been cast with the eyes of the anchor members 15 embedded therein, the ends of the latter are twisted by any suitable means to form a shank 21, the extreme ends being left open as at 22 to provide a chair for supporting reinforcing bars 23 adapted to be embedded in the body portion 12. The bars 23 are laid in the chairs and the open ends of the latter bent around the bars as shown in Fig. 9 and hammered down. The assembled tread portion, anchor members and reinforcing bars thus constitute a rigid assembly. The latter is deposited in a suitable mold with the tread portion 11 down and concrete or the like is poured in the mold to form the body portion 12.

The struts 15 are spaced apart along the bars 23 by a distance less than the length of the struts and form a grid between the bars and tread portion which, with the concrete between the struts, constitutes a truss resisting any bending stress applied to the tread portion.

After the concrete has been poured into the mold, bearing plates 24 are embedded in each end of the block. The plates are preferably of cast iron, are L-shaped in section, and extend the full width of the blocks. They are provided with integral chairs 25 forming seats for engaging the reinforcing bars. The inner horizontal surface of the plates may have pyramidal projections thereon, similar to those on the under surface of the tread plate, and may also have embedded therein wire anchors similar to those shown at 15, and secured to the reinforcing bars.

Holes 26 in alignment with the holes 17 are formed in the body portion by suitable cores. The sides of the body portion taper inwardly toward the bottom. The concrete of which the body portion is formed makes a tight bond with the under-surface of the tread portion, the bearing plates, the anchor members 15 and the bars 23 so that, to all intents and purposes, the resulting block is a unitary member.

The blocks 10 preferably have a length equal to twice the standard center-to-center spacing of railroad ties and a width such that three of the blocks disposed side by side fill up the desired portion of the space between the rails as shown in Fig. 3. The depth of the blocks as also shown in Fig. 3, is approximately equal to the height of the rail above the flange thereof.

In constructing a crossing floor or pavement, the blocks 10 are laid longitudinally on the track with their ends resting on spacers 27 placed on the ties or sleepers. Wooden spacers 28 and 29 are disposed on each side of the rails indicated at 30. The blocks are quite heavy, e. g., approximately 500 lbs., to prevent bouncing under the action of car wheels traversing the track. The blocks may be conveniently handled nevertheless by four men using two of the lifting tools 20. When properly placed, the blocks do not require any attachment to the track or ties, remaining in proper position thereon merely by virtue of

their own weight. In laying the blocks on the ties, the end joints need not be staggered.

The upward taper of the skirt 14 provides grooves between adjacent blocks which may be filled with sealing material 31 to prevent seepage of water through the joints. The downward taper on the body portion 12 facilitates the removal of any block, if desirable for any purpose, as well as the original setting of the blocks on the ties.

The plates 24 as shown in Fig. 2, bear on the spacer blocks 27 resting on alternate ties, and provide durable support-engaging surfaces.

The block of my invention is characterized by numerous advantages over anything known heretofore. In the first place, the blocks are provided with an all-metal tread surface having a uniformly high resistance to abrasion. The blocks are unitary, for all practical purposes. Because of the firm anchorage of the members 15 in the tread portion 11 and their attachment to the reinforcing bars 23, the body and tread portions are firmly bound together. Since one of the members 15 is embedded in each of the projections 16, breakage of the tread portion along the lines of grooves 13 would not permit the chipping out of fragments of the tread portion. Any breakage would follow the lines of the grooves 13 and even if cracks appeared along all such grooves, each separate fragment of the tread portion would be securely anchored to the body portion. The holes 17 and 26 permit circulation of air through the ballast in which the ties are laid to assist in drying it out. They also provide air vents during the vibration of the entire track under the car wheels, thereby preventing the sucking-up of soil particles through the crevices between the ballast rock, and the resulting obstruction to drainage of the latter, as has been experienced with plastic materials laid in a continuous layer to provide a crossing floor or pavement. The blocks can easily be designed to have the desired strength when loaded as a beam supported at the ends of the span between alternate ties and may also be designed to have the weight necessary to hold it in proper position. The blocks are of such character, furthermore, that they may be manufactured at relatively low cost. They are practically indestructible under ordinary conditions and their durability, therefore, is almost unlimited. Since each block rests on only two ties, it is not necessary that the three ties covered by the length of each block be accurately leveled.

Although I have illustrated and described but a preferred embodiment of the invention, it will be recognized that changes in the details of the construction disclosed may be made without departing from the spirit of the invention or the scope of the appended claims.

I claim:

1. A paving block comprising a metal tread portion and a non-metallic body portion, the lower surface of the tread portion having a multiplicity of pyramidal projections, and an anchor embedded in each pyramidal projection and extending downwardly into the body portion, whereby any fracture of the tread will follow the grooves between pyramidal sections, leaving all fragments firmly secured to the body portion.

2. A block adapted for use in railroad crossings or the like, comprising a cast metal tread portion and a non-metallic body portion, the top of the tread portion being roughened to provide

good traction and the bottom of said tread portion having projections which together define intersecting grooves to provide preferred lines of fracture, reinforcing bars embedded in said body portion, and ties each having one end embedded in one of said projections and the other end secured to one of said bars.

3. A paving block adapted for use in railroad crossings or the like, comprising a cast metal tread portion, a non-metallic, reinforced body portion, wire struts having one end embedded in said tread portion and the other end secured to the reinforcement in said body portion, the bottom of the tread portion having a plurality of pyramidal projections, the sides of the bases of adjacent projections being alined and close together, said struts extending into the tread portion substantially through the apices of said projections.

4. A paving block particularly adapted for use on railroad crossings comprising a non-metallic body portion adapted to be supported on sleepers or the like, and a metallic tread portion bonded to said body portion, said body portion having horizontal metal reinforcing bars embedded therein adjacent the bottom thereof, and a plurality of struts also embedded in said body portion, said struts extending vertically between the bars and tread portion, secured to the bars and embedded in the tread portion, and spaced apart along the bars by a distance not greater than their length, thereby forming a grid connecting the tread portion to said bars and constituting, with the material of the body portion therebetween, a truss resisting bending stress applied to said tread portion.

FRANCIS C. SULLIVAN.
